INVENTOR:
Ephraim S. Scripture

UNITED STATES PATENT OFFICE.

ELIPHALET S. SCRIPTURE, OF NEW YORK, N. Y.

WRENCH.

Specification of Letters Patent No. 29,826, dated August 28, 1860.

To all whom it may concern:

Be it known that I, ELIPHALET S. SCRIP-
TURE, of New York, in the county and State
of New York, have invented, made, and ap-
plied to use a new and Improved Wrench;
and I do declare the following to be a full,
clear, and exact description of the same, ref-
erence being had to the accompanying draw-
ings, and to the letters of reference marked
10 thereon, in which—

Figure 1 is a perspective view of my im-
proved wrench; Fig. 2, a sectional view of
the same.

In the drawings like parts of the inven-
15 tion are designated by similar letters of refer-
ence.

The nature of the invention made by me
consists in employing with a wrench, a roller
hung eccentrically within the sliding jaw
20 of the same, as hereinafter described and for
the purpose set forth.

To enable those skilled in the art to make
and use my invention I will proceed to
speak of its construction and operation.

25 In the drawings A shows the handle of
the wrench and B the main shaft of the
same. This main shaft B, is provided with
a ratchet bar C, into which fit the ratchet
teeth *a*, *a*, cut upon the shank D, and so ar-
30 ranged as to adjust the position of the mov-
able jaw E, and in connection with the
spring F attached within the groove *b* of
the corresponding shank G, to retain the
same E in any desired position, when ad-
35 justed.

E shows the movable jaw of the wrench,
adjusted to any desired position by means of
the ratchet teeth *a*, *a* and ratchet bar *c'* as
heretofore set forth.

40 H shows the stationary jaw of the wrench,
cast directly upon the main shaft B.

The movable jaw E is provided with a

groove (*e*) within which is hung eccentric-
ally a roller I, fastened to the same by means
of the pivot (*j*) passing through the mov-
able jaw E and roller I. The edge of this
50 roller (I) is serrated, for the purpose of en-
abling it to grip firmly and securely, the
article to be turned. When desired not to
use the roller I, it is held in position by
means of the spring catch (*l*) placed on the
shank D, and fitting into a slot (*m*) on
roller I.

Among the advantages arising from the
use of my improved wrench may be enum-
erated: First. The roller from its shape will
55 roll to its work and leave it, thus obviating
the necessity of changing the position of the
movable jaw E, to liberate it from its work.
Second. The roller acts as a compensator of
space between the notches on the ratchet-bar,
60 making this mode of adjusting the movable
jaw, available in the stead of the slow screw
now in use for the purpose. Third. The
roller forms a perfect gripper and when
65 rolled back to its place within the movable
jaw, leaves a convenient square nut wrench,
thus combining in one article a wrench and
a gripper.

Having thus described my invention, 70
what I claim as new and desire to secure by
Letters Patent is:

The serrated roller I hung eccentrically
within the movable jaw E in combination
with the spring catch (*l*) arranged and 75
operated in the manner described and for
the purpose set forth.

Witness my hand and seal, this 25th day
of July 1860.

ELIPHALET S. SCRIPTURE. [L. S.]

In presence of—

R. STEWART,
A. SIDNEY DOANE.
